(57) **CLAIM**

The ornamental design for a rodent trap bait cage, as shown and described.

DESCRIPTION

FIG. 1 is a top-rear perspective view of a first embodiment of a rodent trap bait cage, showing my new design;
FIG. 2 is a top-front perspective view thereof;
FIG. 3 is a rear elevational view thereof;

FIG. 4 is a front elevational view thereof;

FIG. 4 is a left side elevational view thereof;

FIG. 5 is a right side elevational view thereof, the left side elevational view being a mirror image of the right side elevational view;

FIG. 6 is a top plan view thereof;

FIG. 7 is a bottom plan view thereof;

FIG. 8 is a cross-sectional view thereof, taken along lines 8-8 in FIG. 4;

FIG. 9 is a bottom-rear perspective view thereof;

FIG. 10 is a bottom-front perspective view thereof;

FIG. 11 is a further perspective view thereof, wherein the rodent trap bait cage is shown deployed on a rodent trap;

FIG. 12 is a top-front perspective view of a second embodiment of a rodent trap bait cage, showing my new design;

FIG. 13 is a top-rear perspective view thereof;

FIG. 14 is a front elevational view thereof;

FIG. 15 is a rear elevational view thereof;

FIG. 16 is a left side elevational view thereof, the right side elevation view being a mirror image of the left side elevational view;

FIG. 17 is a top plan view thereof;

FIG. 18 is a bottom plan view thereof;

FIG. 19 is a cross-sectional view thereof, taken along lines 19-19 in FIG. 14;

FIG. 20 is a bottom-front perspective view thereof;

FIG. 21 is a bottom-rear perspective view thereof;

FIG. 22 is a further perspective view thereof, wherein the rodent trap bait cage is shown deployed on a rodent trap;

FIG. 23 is a top-front perspective view of a third embodiment of a rodent trap bait cage, showing my new design;

FIG. 24 is a top-rear perspective view thereof;

FIG. 25 is a front elevational view thereof;

FIG. 26 is a rear elevational view thereof;

FIG. 27 is a left side elevational view thereof, the right side elevation view being a mirror image of the left side elevational view;

FIG. 28 is a top plan view thereof;

FIG. 29 is a bottom plan view thereof;

FIG. 30 is a cross-sectional view thereof, taken along lines 30-30 in FIG. 25;

FIG. 31 is a bottom-front perspective view thereof;

FIG. 32 is a bottom-rear perspective view thereof; and,

(Continued)

FIG. 33 is a further perspective view thereof, wherein the rodent trap bait cage is shown deployed on a rodent trap. The broken lines in FIGS. 1-33 are for the purpose of illustrating portions of the rodent trap bait cage and environmental structure that form no part of the claimed design.
